CLAIM

The ornamental design for a cardholder stick, as shown and described.

DESCRIPTION

FIG. 1 is a front side perspective view of the subject cardholder stick, showing the design of a butterfly as the center portion;

FIG. 2 is a front side elevation view of the subject cardholder stick;

FIG. 3 is a rear side elevation view of the subject cardholder stick, opposite the front side thereof;

FIG. 4 is a first lateral side elevation view of the subject cardholder stick;

FIG. 5 is a second lateral side elevation view of the subject cardholder stick, opposite the second lateral side thereof;

FIG. 6 is a top plan view of the subject cardholder stick; and, FIG. 7 is a bottom plan view of the subject cardholder stick, opposite the top plan view thereof.

The broken lines in the drawings are included for illustrating portions of the article that form no part of the claimed design.
